INVENTOR:

Albert Danzer
BY M. M. & C.
ATTORNEYS

UNITED STATES PATENT OFFICE.

ALBERT DANZER, OF HAGERSTOWN, MARYLAND.

WATER-TIGHT SKYLIGHT.

SPECIFICATION forming part of Letters Patent No. 472,438, dated April 5, 1892.

Application filed March 4, 1891. Serial No. 383,800. (No model.)

To all whom it may concern:

Be it known that I, ALBERT DANZER, residing at Hagerstown, in the county of Washington and State of Maryland, have invented certain new and useful Improvements in Skylights, of which the following is a specification.

My invention relates more particularly to water-tight skylights; and it has for its object to provide a skylight of this character which 10 will embody the elements of simplicity, cheapness, effectiveness, and which can be conveniently handled and easily put in position.

My invention consists in the peculiar combination and novel arrangement of parts, all 15 of which will hereinafter be fully described in the specification and pointed out in the claims, reference being had to the accompanying drawings, in which—

Figure 1 is a plan view of a skylight constructed according to my invention. Fig. 2 is a cross-section of the same, taken on the line 2 2, Fig. 1. Fig. 3 is a similar view taken on the line 3 3, Fig. 1. Fig. 4 is a detail perspective view of a portion of the skylight. 25 Fig. 5 is a detail plan view hereinafter referred to.

Referring to the accompanying drawings, A indicates the supporting-frame on which is mounted the skylight, which consists of the 30 wooden end timbers A', on the inner face of which are held the side troughs B, formed of galvanized iron bent up, as most clearly shown in Fig. 2, by reference to which it will be seen that they have oppositely-extended flanges b, 35 which rest upon and are secured to the upper face of the timbers A', and inwardly-projecting flanges b', which serve as end supports for the glass sections C.

D indicates cap-plates, which fit over the 40 upper face of the bars A' and which are secured to such bars by means of screws d. The inner ends of such plates are projected over the flanges b' and formed into clamp members having downturned ends d', which 45 fit against the glass and serve to hold it in place, the outer portions of the plates D being bent down, as at D', such bent portions extending below the bar A' to cover the joint between it and the frame-timber A on which 50 it is secured.

When two or more glass sections are used, a center rib or support is provided, which con-

sists of a double metallic trough-section B', formed with a central supporting portion B², which is held on a cross-bar E by a cap-plate 55 D³, which projects over the adjacent ends of the glass sections, which are supported on the oppositely-projecting flanges b, to which are soldered the upper ends h of an angle-brace H, as shown.

F indicates a screw, which serves to hold the cap-plate D³ on the cross-bar E.

J indicates the bottom timber of the skylight-frame, which is secured at its ends to the end bars A', and upon this timber is 65 mounted a bottom trough K, arranged to receive any water that may condense on the under side of the glass, and such trough, which is most clearly shown in Figs. 3 and 4, is formed of a L-shaped metallic body, the 70 lower bent flange of which is extended up to a point above the glass sections, the upper edge being folded on the inside and bent inward to form a ledge k⁵ for the lower ends of the glass sections to rest on and to receive the 75 putty to bed the glass in, whereby to make a perfectly-tight joint. The inner upturned flange k' does not extend up to the under face of the glass, whereby a passage k² is formed to permit the condensation to run down into 80 the trough K, from which it is discharged through the opening k³ in the lower flange k, and to avoid the possibility of any water entering between the timber J and the supporting-frame a guard-plate L is inserted under 85 the trough K, which is formed with a downwardly-bent flange L', which extends over the front, as shown.

By reference to Fig. 4 it will be noticed that the ends of the troughs B project through 90 the lower flanges k of the trough K to admit of the ready discharge of the water collected therein. The upper portion of the skylight-frame is constructed in substantially the same manner as the end pieces, the abutting ends 95 of the flanges b being mitered, as shown, and soldered tight, reinforcing-plates N (shown in dotted lines) being secured to the under face of the mitered ends, which serve to add additional strength and render the joint the more 100 safe from leaking. The troughs B and K are soldered together at O to hold the several frame-sections the more secure and watertight.

From the foregoing description, taken in connection with the drawings, the advantages of my improvements will be readily understood.

Having thus described my invention, what I claim, and desire to secure by Letters Patent, is—

1. In a water-tight skylight, the combination, with the end timbers A', the troughs B, arranged on the inner faces thereof, formed with oppositely-projecting flanges b b', the flanges b forming the support for the trough B on the timbers A', and the glass section C, supported on the flanges b' of the cap-plates D, held on the timbers A' on the flanges b and having clamp portions adapted to project over the troughs B and clamp the glass on the flanges b', and means for securing the plates D on the timbers A', all arranged substantially as shown, and for the purposes described.

2. The combination, with the main supporting-frame A, the timbers A', the trough B, the glass C, arranged as shown, of the cap-plates D, adapted to be secured to the upper face of the timbers A', said cap-plates formed with clamp portions adapted to engage the glass C

and with a downwardly-extending flange D', adapted to overlap the outer edge of the timbers A' and projected over the joint between such timbers and the frame-timbers A, all arranged substantially as and for the purpose described.

3. The combination, with the glass sections C C, of the bar E, the double trough-section B' B', formed with a central portion supported on the top of the bar E and with oppositely-projecting side flanges b, forming supports for the glass sections, the cap-plates D', secured to the upper face of the bar and adapted to hold the trough-section B' B' in place and formed with oppositely-extending clamp portions arranged to clamp the adjacent ends of the glass sections on the flanges b b', and the angled braces H, fitted over the lower ends of the bar E and secured at their upper ends to the flanges b, as and for the purpose described.

ALBERT DANZER.
